UNITED STATES PATENT OFFICE.

GASPER A. WAGNER, OF PORTLAND, INDIANA.

STEAM-GENERATOR.

SPECIFICATION forming part of Letters Patent No. 251,006, dated December 13, 1881.

Application filed July 5, 1881. (No model.)

To all whom it may concern:

Be it known that I, GASPER A. WAGNER, a citizen of the United States, residing at Portland, in the county of Jay and State of Indiana, have invented certain new and useful 5 Improvements in Steam-Generators; and I do hereby declare the following to be a full, clear, and exact description of the invention, such as will enable others skilled in the art to which 10 it appertains to make and use the same, reference being had to the accompanying drawings, and to the letters or figures of reference marked thereon, which form a part of this specification.

15 My invention relates to improvements in steam-generators in which tubes are employed to increase the heating-surface thereof; and the object of my invention is to provide novel means for preventing injury to such generators 20 in the event of the water therein being allowed to fall below a certain point. I attain this object by means of the devices illustrated in the accompanying drawings, in which—

Figure 1 is a sectional elevation of a generator of the locomotive type, showing how it 25 may be constructed and how my improvements may be applied thereto. Fig. 2 is a sectional elevation, showing a portion of the tube-sheet 30 of a steam-generator, nuts and washers or gas- kets for securing the tubes therein, the differ- 35 ent sections of a tube made according to my plan, and a soft-metal ferrule for uniting the parts of the tube; and Fig. 3 is a sectional elevation of the soft-metal ferrule, the screw- 40 threads in its ends for receiving the outer sec- 45 tions of the tube, and the short central section of tube in position.

Similar letters refer to similar parts through- 45 out the several views.

Various expedients have heretofore been re- 50 sorted to for the purpose of preventing injury to steam-generators when, through accident or carelessness, the water in them has been allowed to fall to such an extent as to leave the metal 55 composing the crown-sheet of the fire-box or the tubes exposed to too high a degree of heat. The devices used for such purpose have gen- 60 erally consisted of a plug having a hole bored through it, said hole being filled with some 65 kind of metal or an alloy of metals that would melt at a lower temperature than that required

to permanently injure the tubes. This method has been found to be deficient as a protector of the tubes, as it has to be placed in positions where the temperature is liable to vary very 55 much from that to which the tubes are exposed.

My invention is designed to obviate this difficulty by placing the metal to be melted, when occasion occurs, upon the tube or tubes of the generator, and consequently where it is sub- 60 jected to about the same temperature as is the tube.

My improvement is applicable to all forms of steam-generators in which tubes are em- 65 ployed through which the heated gases pass from the fire-box to the atmosphere, whether they are horizontal or vertical.

The form of generator chosen for the pur- 70 pose of showing the application of my improve- 75 ment is of the locomotive type, A referring to such a generator, the flues or tubes B B of which pass through the horizontal portion thereof, and are held in tube-sheets c c' pro- 80 vided with the requisite apertures for receiv- 85 ing them. One or more of these tubes are made to consist of the sections or parts B', B², and B³, as shown in Fig. 2, the inner ends of the portions B' and B² being provided with screw-threads, while the central portion, B³, is a plain ring of metal of any desired length, 80 and of equal diameter with the other sections. This central portion is inclosed in a ferrule, B⁴, of some form of metal or an alloy of metals—such, for instance, as an alloy made of two parts of tin and one of bismuth, or any other 85 alloy or metal that will not melt in the water contained in the generator, but that will melt at a less temperature than that required to injure the tubes. This ferrule may be cast upon the portion B³ of the tube, or it may be se- 90 cured thereon by having a thread cut upon its inner surface throughout its entire length; and the central portion, being provided with a thread upon its outer surface, may be screwed upon said portion. In either case there is to be a 95 thread in each end of the ferrule B⁴, as shown in Fig. 3, for the reception of the inner ends of the portions B' and B² of the tube B, which are to be screwed into said ferrule until their ends come in contact with the ends of the central portion, B³. When thus constructed the 100 tubes will remain intact while in use until the

temperature to which they are subjected becomes sufficiently high to melt the ferrule B^4 , when it will disappear, and allow the portion B^3 to fall out of its place, which will have the 5 effect to allow steam to pass into the fire-box and extinguish the fire, or at least deaden it to such an extent as to prevent an increase of the temperature. The method of securing these tubes in the tube-sheets is clearly shown 10 in Fig. 2, where it will be seen that two nuts, D D' , are employed, the former being placed upon the inside of the sheet and the latter outside thereof. Between the nut D and the tube-sheet there is placed a conical gasket or 15 ring, D^2 , and between the nut D' and the sheet a washer of copper. When the tubes have been placed in the sheets the nuts are screwed down upon the washers, which forms a tight joint and at the same time holds the tubes in 20 position.

In practice any number of the ferrules may be used, each tube, if desired, being supplied with one, as shown in the drawings; but as a rule from one to three will be found sufficient.

25 When used in a vertical generator the proper location of the ferrule or ferrules will be found to be, say, six inches above the lower tube-sheet.

I contemplate the use of the devices shown and described for holding the tubes in their 30 sheets in all kinds of generators which employ tubes, whether such tubes are provided with devices for their own protection or otherwise.

I also contemplate the use of the fusible ferrule with a tube made of two sections screwed 35 into its ends, in which case the result accomplished will be the same as or similar to that produced when three sections are used.

Having thus described my invention, what I claim, and desire to secure by Letters Patent, is—

A tube for steam-generators, consisting of two or more sections or parts terminating in a ring or ferrule of metal, or of an alloy of metals, the melting-point of which is below that of the 45 tube upon which it is used, it being for the purpose set forth.

In testimony whereof I affix my signature in presence of two witnesses.

GASPER AUGUSTUS WAGNER.
